UNITED STATES PATENT OFFICE.

JEFFIE WATKINS HARDIE, OF SOURLAKE, TEXAS, ASSIGNOR OF ONE-FIFTH TO SMITH, CRAWFORD & SONFIELD AND MACKEY, OF JEFFERSON COUNTY, TEXAS, A FIRM.

WATER-HEATER.

953,690.

Specification of Letters Patent.

Patented Apr. 5, 1910.

Application filed June 10, 1908. Serial No. 437,716.

To all whom it may concern:

Be it known that I, JEFFIE W. HARDIE, a citizen of the United States, and a resident of Sourlake, in the county of Hardin and State of Texas, have made certain new and useful Improvements in Water-Heaters, of which the following is a specification.

My invention relates to improvements in feed water heaters and has for its object to provide an improved apparatus for the rapid and economical heating of water for steam purposes in oil and gas burning boilers.

My invention consists in certain novel features of construction, arrangement and combination of parts as will be hereinafter fully described and pointed out in the claims, reference being had to the accompanying drawings, in which—

Figure 1 is a perspective view of a boiler furnace showing location of my improvement. Fig. 2 is a rear view of the "target". Fig. 3 is a section taken on line 3—3 of Fig. 2. Fig. 4 is a section taken on line 4—4 of Fig. 2.

In carrying out my invention I use a plate A of cast iron, which may be square or oblong and may be from one-half to one inch in thickness, this plate being termed the "target". This plate is set up inside the boiler furnace in place of the fire brick "target" used in oil burning boilers. To the back of the target is secured the pocket B, which, as shown, is enlarged at its central portion B⁴ and narrows down toward its ends where the connections for the feed water pipe are made. The incoming feed water enters the pocket B at end B' and after passing diagonally across the target, that being the position of the pocket, discharges at the end B², that is, the water from the feed pipe on its way to the boiler feed connections will pass immediately back of the target plate and through the pocket, passing directly opposite and back of the point where the jet of burning fuel oil is thrown against the plate. The pocket B will be approximately three times the capacity of the same length of straight feed pipe, thus permitting the water to pass slowly by the point where the fire is hottest, thus becoming already heated before it reaches the boiler feed connections. The base of the target plate is made with a flange B³ extending rearwardly and bent at such

an angle that the target plate stands at an angle of about 35°; by thus inclining the target plate backward the heat thrown against the target plate from the oil jet is deflected upward and toward the boiler flues, and thus avoiding waste of heat. In the event it is desired to use more than one boiler, or, what is known as a "battery" of boilers, these plates or targets may be connected by the feed pipe, and, the water instead of passing from the first target or heating point into the first boiler, will pass through the heat of all the boilers in the battery, and is fed back hot into the other boilers by means of ordinary feed lines or feed columns, thus greatly reducing the amount of fuel oil or gas required for producing the necessary amount of steam. These targets may be made in any desired size, for use in connection with the various sizes and kinds of boilers used.

The front of the target will be protected by a facing of fire brick or other heat resisting medium, held thereon in any suitable manner. The target plate may be made in sections which can be readily passed through the furnace door, and then assembled and held together in a single plate by tongues and grooves, or other suitable means. The target itself may constitute the circulating medium for the feed water, it only being necessary that such medium shall be interposed in the path of the injected flame. The flange B³ may also be dispensed with as the feed water pipe connections will form a sufficiently strong support to maintain the target in its desired position. By inclining the target the full force of the flame is not allowed to get to the boiling flues as such would soon burn them out.

I claim—

1. A device for heating feed water in oil or gas burning boiler furnaces, consisting of a target plate mounted within the fire box and inclined upwardly and rearwardly in the fire box, a pocket located at the rear of said plate, said pocket having connection at one end with feed supply, and at the other end with the boiler feed connections.

2. A device for heating feed water in oil or gas burning boiler furnaces, consisting of a target plate having a bent base to cause the plate to set at an angle and project upwardly and rearwardly in the fire box, a pocket located at the back of the plate to

serve as a passage for feed water, said pocket being enlarged in its central portion, and having connection at one end with the feed water supply and at the other with the 5 boiler feed connections.

3. A device for heating feed water in oil or gas burning boiler furnaces, consisting of a target plate having a flanged base disposed at an angle to cause the plate to assume a rearwardly inclined position, a pocket located at the back of the plate and extending diagonally across the same, said pocket serving as a passage for feed water and having a connection at one end with 10 the feed water supply and at its other end with the boiler feed connections.

4. A device for heating feed water in oil or gas burning boiler furnaces, consisting of a metal plate having an angularly disposed 20 base flange, a pocket placed at the back of said plate extending diagonally across the same, and having its central zone enlarged, said pocket serving as a passage for the feed water, and having a connection at one end 25 with the feed water supply, and at its other end with the boiler feed connections.

5. A device for heating feed water in oil or gas burning furnaces, consisting of a feed water conducting medium located within 30 the fire box and tilted rearwardly at an angle from the vertical, and positioned to re-

ceive and deflect upwardly and rearwardly the flame of an injector burner.

6. A device for heating feed water in oil or gas burning furnaces, consisting of a target plate constituting a feed water medium, tilted rearwardly at an angle from the vertical, and positioned in the fire box of the furnace to intercept and deflect upwardly and rearwardly the flame of an injector 35 burner.

7. A device for heating feed water in oil or gas burning furnaces consisting of a target plate placed within the fire box of the furnace and inclined upwardly and rearwardly, a pocket forming part of said plate and having connection at one end with the feed water supply and at the other end with the boiler feed connection, said feed water and boiler feed connections supporting and 40 holding the target plate in position within the fire box.

8. A device of the class described comprising an oil discharge nozzle, a target in the path thereof and constituting a feed 45 water heater, and means for directing water to and from the target.
